CLAIM

The ornamental design for a shipping case, as shown and described.

DESCRIPTION

FIG. 1 is a left side elevational view of a shipping case showing my new design; the right side elevational view being a mirror image thereof;

FIG. 2 is a front elevational view thereof; the rear elevational view being a mirror image thereof; and,

FIG. 3 is a top plan view thereof; the bottom plan view being plain and unornamented.

1 Claim, 3 Drawing Sheets

FIG. 1

FIG. 2

FIG. 3
